UNITED STATES PATENT OFFICE

171,637

LAMP

Yuk Tong Char, Honolulu, Territory of Hawaii

Application April 2, 1953, Serial No. 24,324

Term of patent 7 years

(Cl. D48—20)

To all whom it may concern:

Be it known that I, Yuk Tong Char, a citizen of the United States, residing at Honolulu, in the territory of Hawaii, have invented a new, original, and ornamental Design for a Lamp, of which the following is a specification, reference being had to the accompanying drawing, forming part thereof.

I claim:

The ornamental design for a lamp, as shown.
YUK TONG CHAR.
